Section G-60, Vest Restraint with Shoulder Ties.

Primary Examiner—Bernard Ansher

[57] CLAIM

The ornamental design for a body restrainer, as shown and described.

DESCRIPTION

FIG. 1 is a top perspective view of a body restrainer showing our new design;

FIG. 2 is a perspective view with the body restrainer in an alternate position;

FIG. 3 is a rear perspective view thereof;

FIG. 4 is an enlarged side view of the restrainer;

FIG. 5 is a view as seen from the side opposite FIG. 4; and

FIG. 6 is an enlarged fragmentary elevation of the netting material, shown for clarity of illustration.

The broken lines are shown for illustrative purposes only.
